UNITED STATES PATENT OFFICE.

JOHN PRIMROSE, OF DONGAN HILLS, NEW YORK, ASSIGNOR TO POWER SPECIALTY COMPANY, OF NEW YORK, N. Y., A CORPORATION OF NEW YORK.

STEAM-SUPERHEATER.

1,132,211.

Specification of Letters Patent. Patented Mar. 16, 1915.

Application filed May 16, 1914. Serial No. 838,970.

To all whom it may concern:

Be it known that I, JOHN PRIMROSE, a subject of the King of Great Britain, residing at Dongan Hills, county of Richmond, 5 and State of New York, have invented certain new and useful Improvements in Steam-Superheaters, of which the following is a full, clear, and exact description.

The invention which constitutes the subject matter of this application relates to improvements in a superheater especially adapted in its use to traction engines.

This invention has particularly to do with that type of superheater in which the individual superheating elements are projected rearwardly from the smoke-box into the fire tubes of the boiler, and the invention pertains largely to the construction of the superheater headers and superheating elements and the relation of the same to the smoke box of the traction or other engine.

In the drawings, Figure 1 is a longitudinal section of the forward portion of a traction engine, illustrating the manner in 25 which the superheater is secured to the boiler. Fig. 2 is a section taken on the line 2—2 of Fig. 1. Fig. 3 is a top plan view illustrating the header supporting brackets.

Referring now in detail to the drawings, 30 the reference numeral 10 designates the forward portion of a traction boiler provided with the usual fire-tubes 11, tube sheet 12, smokestack 13, and steam dome 14. The headers 15 are supported preferably by 35 means of brackets 17 located on the interior of the smoke stack, and by brackets 17^a on the outside of the smoke box. To give proper stability to the headers, I employ suitable securing means 18 which are connected to these brackets on the outside of 40 the smoke box, as clearly shown in Fig. 2.

One of the important features of this invention consists in making provision for removing the complete superheater as a unit 45 from the boiler without breaking the joints between the superheater tubes and the headers. This is accomplished by providing slots 19 on either side of the shell of the smoke box running longitudinally thereto, 50 and extending to the front end of the shell. It will therefore be seen that when the plates 20, which cover these slots, are removed, and the inlet and outlet steam pipes 21 and 22 disconnected, the headers and superheater

elements may be removed or assembled as a 55 unit.

The saturated steam from the boiler is supplied to the header by means of the pipe 21 and the superheated steam is supplied to the engine by means of pipe 22. Both of 60 said pipes are shown only diagrammatically, as it will be obvious to anyone skilled in this art how to make the connections between the superheater and boiler on the one hand and between the superheater and the engine on 65 the other.

From Fig. 2 it will be observed that the arrangement of superheater tubes is such that any one unit may be removed without necessarily disturbing any other. Each 70 header is preferably provided with an opening opposite each superheater tube opening to give access to the superheater tube ends, whereby the latter may be more readily expanded into or removed from the headers. 75

What I claim is:

1. A boiler provided with fire tubes, in combination with a superheater, comprising transversely arranged inlet and outlet headers and superheating units, the latter projecting rearwardly into said fire tubes, the smoke box of said boiler provided with longitudinal slots extending to the front end of the shell for receiving the ends of the headers, and means for securing said headers in the said slots. 80

2. A boiler provided with fire tubes and the shell of which is provided with longitudinal slots extending to the front end of the smoke box, in combination with a superheater comprising transversely arranged inlet and outlet headers supported in said slots and superheater elements projecting rearwardly into said fire tubes, and means for removably securing said headers in said 90 slots, whereby the entire superheater may be removed as a unit. 95

3. A boiler provided with fire tubes and the shell of which is provided with longitudinal slots extending to the front end of the smoke box, in combination with a superheater comprising transversely arranged inlet and outlet headers supported in said slots, means for connecting the saturated steam header with the steam dome of the 100 boiler, means for connecting the superheated steam header with the steam chest, superheating elements connected to said headers, 105

the coils of which project rearwardly into said fire tubes and the inlet and outlet ends of which are expanded into the inlet and outlet headers, and means for removably securing said headers in said slots, whereby said headers and said elements may be removed as a unit.

In testimony whereof I affix my signature in the presence of two subscribing witnesses.

JOHN PRIMROSE.
